UNITED STATES PATENT OFFICE

KENNETH J. TOBIN, OF CHICAGO, ILLINOIS, ASSIGNOR TO CAMEL COMPANY, OF CHICAGO, ILLINOIS, A CORPORATION OF ILLINOIS

DOOR-OPERATING MECHANISM

Application filed May 3, 1928. Serial No. 274,708.

This invention relates to improvements in door operating and sealing mechanism, and more especially such a mechanism for slideable doors of house cars.

One object of my invention is to provide an efficient combined door opening, closing and locking mechanism for slideable doors which consists of the minimum number of parts capable of carrying out the three functions indicated.

Another object of my invention is to provide a mechanism of the character indicated, such that, when the usual car sealing ribbon has been removed, the operator is enabled to unlock the mechanism and impart the initial opening movement to the door by a simple manipulation of a single actuating lever and without the necessity of otherwise using his hands.

More specifically, an object of my invention is to provide a mechanism for the purpose described wherein are employed a hasp-link, a hasp-staple and an actuating lever so arranged that the hasp-link may first be unlocked, then disengaged from its hasp-staple, even when under heavy friction, and then actuated by manipulating the lever, to the end that the operation may be facilitated and speeded up.

Other objects of my invention are to provide a mechanism of the type indicated which is adapted for holding the door in a partially open or ventilating position; to provide means whereby the actuating lever may be locked when not in use, and the door in open position, whereby to prevent unrestrained swinging or flapping of the lever when the car is in motion.

In the drawings forming a part of this specification, Fig. 1 is a broken elevational view of portions of double doors of an automobile car, showing my improvements applied thereto, the doors being in fully closed position and the mechanism locked. Fig. 2 is a view similar to Fig. 1, but illustrating the condition of the parts when the door is in partially open or ventilating position. Fig. 3 is a view similar to Fig. 1, but illustrating the position of the actuating lever when unlocked, and indicating the first step in the

operation. Fig. 4 is a vertical sectional view corresponding to the line 4-4 of Fig. 3, and indicating more particularly the manner of disengaging the hasp-link from its staple. Fig. 5 is a horizontal sectional view corresponding to the line 5-5 of Fig. 3. Fig. 6 is a view similar to Fig. 1 illustrating another embodiment of the invention. And Fig. 7 is a vertical sectional view corresponding to the line 7-7 of Fig. 6.

In said drawings, and referring first to the construction illustrated in Figs. 1 to 5, inclusive, 10 indicates the main door and 11 the auxiliary door of an automobile car and to which my improvements are applied. As understood by those skilled in the art, the auxiliary door will be locked against slideable movement while the main door 10 is being opened or closed. In the embodiment chosen for illustration, the actuating lever and lock are shown applied to the auxiliary door and the hasp-link to the main door, but it will be understood by those skilled in the art that this arrangement may be reversed and also that the improvements are equally adaptable to a house car or equivalent, having only a single door, and that the actuating lever and lock may be applied either to the fixed framework or to the movable door.

In carrying out my invention, I employ a hasp-link 12, an attaching plate 13 therefor, an actuating lever 14, an attaching plate or bracket 15 therefor, and a locking arrangement, the details thereof being hereinafter described.

The doors 10 and 11 are of well known construction, of the sheet metal type. The main door 10 is provided at its forward edge with a vertically extending corrugation 16 reinforced on the inner side thereof by a strip 17 and outwardly of the corrugation there is secured to the edge of the door a combined bracing and weather sealing bar 18. Merging with the vertical corrugations 16 are horizontal corrugations 19 and the attaching plate 13 is preferably so formed as to fit over one of the corrugations 19 and riveted to the crest thereof. At the end of the plate 13 nearest the forward edge of the door, a loop section 20 is formed, having a shouldered tip

21 hooked through the corrugation 16 and strip 17, as best shown in Fig. 5. The hasp-link 12 is loosely pivotally mounted on the loop section 20, to adapt the same for swinging vertically and horizontally with respect thereto.

5 The auxiliary door 11 is constructed similarly to the door 10, said door 11 having a vertically extending corrugation 22, with a reinforcing strip 23 therewithin and horizontal corrugations 24 merging with the vertical corrugation 22. At its forward edge, the door 11 has a combined reinforcing and weather sealing bar 25, the latter having a 10 forwardly and slightly outwardly inclined flange 26 beneath which seats the bar 18 of the main door 10.

15 The attaching plate or bracket 15 for the actuating lever has one section 27 thereof conformed and riveted to the crest of one of the horizontal corrugations 24 and has another vertically and forwardly extended section 28 conforming and riveted to the vertical corrugation 22 and the flat marginal portion 29 of the door 11, as best indicated in Fig. 5. As will be understood, the attaching plates or brackets may be modified so as to fit any particular design of door to which applied.

20 The bracket 15, in line with the hasp-attaching plate 13, is formed with an outwardly extended lug 30, the same being outwardly tapered and having a recess 31 therein, thus providing a staple for the hasp or link 12, the latter having a suitable elongated opening 32 therein adapting the same to be fitted over the staple or lug 30.

25 On the upwardly extended section 28 of the bracket 15 is formed an outstanding boss 33 and integrally formed with the latter is a slightly tapered journal 34, as best shown in Figs. 4 and 5. Slidably and rotatably mounted on the journal 34 is a loop-shaped hanger 37, the latter being prevented from becoming disengaged by a washer 36 overlapping the side arms of the loop hanger 37, said washer being secured by a rivet 35 passing through the journal 34.

30 At its upper end, the hanger 37 is provided with an upwardly projecting centrally disposed flange 38, to which is pivotally connected, as by rivet 39, the upper looped end 40 of the actuating lever 14. Said upper looped end 40 is so formed as to readily straddle or surround the loop hanger 37 so that the actuating lever may be in either the plane of the hanger or swung outwardly therefrom, the latter condition being illustrated in Fig. 4. With this mounting, it is evident that the lever 14 may be swung about two different axes and also may be bodily shifted in a vertical direction for the purposes hereinafter indicated.

35 The lever 14 is provided with a relatively elongated depending handle 41 and also has

40 integrally formed therewith, and laterally offset from the lower portion of the loop section 40, an arm 42 from which depends a finger or bolt 43 adapted to enter the opening 31 of the hasp lug 30. At the upper end of the finger 43 an outwardly extended shoulder 44 is formed, the same having an opening 45 therethrough in alignment with the opening 31 so that the usual ribbon of a railway car seal may be passed through both parts and the mechanism sealed in the usual manner. With the parts as shown in Figs. 1 and 5, it is evident that the actuating lever 14 overlies the hasp-link 12 and consequently when the pin or bolt 43 is in the position shown, neither the lever can be actuated nor the hasp-link disengaged from the lug without breaking the seal.

45 The link 12 is formed with an upwardly curved end section indicated at 46, within which is formed an elongated opening 47 having a restricted mouth or entrance 48. The opening 47 and the shoulders at the opposite ends formed thereby, are provided to cooperate with a heavy stud 49 having a flanged head 50, which is integral with the handle portion 41 of the actuating lever. It will be noted also that a cam guiding surface 51 is formed on the lower edge of the link for guiding the lug and link into interlocking engagement as the lever is swung clockwise from vertical position.

50 The operation of the improved mechanism is as follows, assuming that the parts are in locked position shown in Fig. 1. After the breaking of the seal, the lever 14 is pushed vertically to the position shown in Fig. 3, which removes the bolt 43 from the hasp lug. Incidentally, it will be noted that the flanged head 50 of the lug 49 will engage under the hasp-link 12 whereupon, upon pulling the lower end of the lever outwardly, as indicated in Fig. 4, the link 12 will be positively disengaged from the staple or lug 30. This is of importance, since it frequently happens that the hasp is engaged very tightly with its lug or staple when used on car doors and considerable leverage is required to disengage the same.

55 With the link 12 disengaged, as shown in Fig. 4, the operator swings the lever 14 clockwise until the lug 49 enters through the mouth 48 into the opening 47 of the link, it being observed that the link cannot fall away from the lever during this operation, by reason of the flanged head 50. With the lever and link thus interlocked, the lever may be lowered to its normal position and then swung counter-clockwise, thus forcing the door open. When the door has been opened sufficiently, the link may be readily disengaged from the lever, as will be obvious. The door will be closed and locked by reversing the sequence of operations just described.

60 In Fig. 2 is shown a condition where the

main door 10 is only slightly opened, as may sometimes be required for ventilation and it will be observed that the lever and link are interlocked and the lever locked against swinging by the pin or bolt 43 being entered through the opening of the staple lug 30. It will further be observed that the lever 14 may be retained in its vertical position when the link 12 is entirely disengaged therefrom, as when the door is fully open, thus preventing the lever from swinging either outwardly from the face of the car or back and forth in a plane parallel thereto and minimizing the danger of breakage of the lever when the car is in motion.

Referring next to the construction illustrated in Figs. 6 and 7, the attaching plate 113 and link 112 are the same as the two corresponding parts previously described.

The plate or bracket 115 is similar to the plate 15 but is slightly modified so as to provide a higher or deeper shelf 60 from which is projected outwardly the staple or hasp lug 130.

The actuating lever 114 is mounted on the bracket 115 in the same manner as the lever 14 except that the boss 33 of the first described construction is omitted, hence bringing the lever in a normal plane closer to the door than in the first described construction. The differences are for the purpose of positioning the lever 114 beneath the link 112 and because of this change, the arm 142 on the lever is outwardly as well as laterally offset, so as to bring the locking finger or bolt 143 in proper position with respect to the lug 130. The stud 149 of the lever is on the outer side because of the reversed position of the link.

The operation of the construction just described is manifestly the same as that first described, with the difference that the hasp-link is disengaged from its lug or staple by the main part of the lever 114 instead of by the flanged head of the stud, as in the first described form.

As evident from the preceding description, the mechanism comprises the minimum number of parts capable of carrying out the three functions of imparting opening movement to the door, imparting closing movement thereto, and locking the operative parts. Further, in opening the door, the operator merely grasps the actuating lever and thereafter does not have to use either hand for effecting any engagement or interlocking of the parts. All parts are of such design that the same may readily be manufactured in the form of forgings, which are generally preferable to malleable castings.

I have herein shown and described what I now consider the preferred manner of carrying out my invention, but the same is merely illustrative and I contemplate all

changes and modifications that come within the scope of the claims appended hereto.

I claim:

1. In a door operating and locking mechanism, the combination with an actuating element; of an operating element; and devices for locking the actuating element when the door is in closed position including means carried by the actuating element. 70
2. In a door operating and locking mechanism, the combination with an actuating element; of an operating element; means for locking said actuating element, said means being engageable and releasable solely upon and by movement of the actuating element. 75
3. In a door operating and locking mechanism, the combination with an actuating lever; of a link; and devices for locking said lever when the door is in closed position including means carried by the lever. 80
4. In a door operating and locking mechanism, the combination with an actuating lever; of a link; and means for locking said lever, said means being engageable and releasable solely upon and by movement of the lever. 90
5. In a door operating and locking mechanism, the combination with an actuating lever; of a hasp-link; a hasp-staple; a pin lock cooperable with said staple, said lock being carried by said lever. 95
6. In a door operating and locking mechanism, the combination with an actuating lever; of a hasp-link; a hasp-staple; a pin lock cooperable with said staple; and means for disengaging the pin lock from the staple upon and by movement of said lever. 100
7. In a slidable door opening and closing mechanism, the combination with an actuating lever; of an operating element; and cooperable means on the lever and element automatically engageable to interlock when and as the lever is manually swung in one direction, whereby the operating element may then be forced to move the door. 105
8. In a slidable door opening and closing mechanism, the combination with an actuating lever; of a pivotally mounted link; and cooperable means on the lever and link automatically engageable to interlock when and as the lever is manually swung in one direction. 115
9. In a slidable door opening and closing mechanism, the combination with an actuating lever; of a hasp-link; a hasp-staple with which the link is adapted to cooperate; and cooperable means on said lever and link automatically engageable to interlock when and as the lever is manually swung in one direction. 120
10. In a door operating and locking mechanism, the combination with an actuating element having a handle portion; of an operating element; detachable cooperable interlocking means on said elements adapted, when engaged, to impart movement to the operating 130

element; and means for locking the actuating element against movement while interlocked with the operating element when the door is in a partially open position.

5 11. In a door operating and locking mechanism, the combination with an actuating element having a handle portion; of an operating element; detachable cooperable interlocking means on said elements; and means, in-

10 cluding a section movable with the actuating element, for locking the latter against movement when interlocked with the operating element and while the door is in a partially open position.

15 12. In a door operating and locking mechanism, the combination with an actuating lever having a handle portion; of a pivoted link; detachable cooperable interlocking means on said lever and link; and means for locking said lever against movement while interlocked with the link and when the door is in a partially open position.

20 13. In a door operating and locking mechanism, the combination with an actuating lever; of a pivoted operating link; detachable interlocking means on said lever and link; and means, including a portion integral with the lever, for locking the latter against movement while interlocked with the link and when

25 the door is in a partially open position.

14. In a door operating and locking mechanism, the combination with an actuating lever; of a hasp-link; a hasp-staple cooperable with said link; detachable interlocking means

30 on said lever and link; and means for locking the lever and link while interlocked when the door is in partially open position.

35 15. In a door operating and locking mechanism, the combination with an actuating element; of an operating element; cooperable means on said elements automatically engageable to interlock when and as the actuating element is moved in one direction; and devices for locking the actuating element

40 when the door is in closed position, said devices including means carried by the actuating element.

16. In a door operating and locking mechanism, the combination with an actuating element; of an operating element; cooperable means on said elements automatically engageable to interlock when and as the actuating element is moved in one direction; and devices for locking the actuating element

45 when the door is in closed position, said devices including means releasable upon and by movement of the actuating element.

17. In a sliding door opening, closing and locking mechanism, the combination with an actuating lever; of an operating link; cooperable means on said lever and link automatically engageable to interlock when and as the lever is manually swung in one direction; and devices for locking the lever including means

50 carried by the lever.

18. In a sliding door opening, closing and locking mechanism, the combination with an actuating lever; of a hasp-link; a hasp-staple cooperable therewith; cooperable means on said link automatically engageable to interlock when and as the lever is manually swung in one direction; and means for locking said lever, said means being releasable upon and by movement of the lever.

70 19. In a door operating and locking mechanism, the combination with an actuating lever; a support on which said lever is mounted; a fixed element carried by said support; means integral with the lever and cooperable with said fixed element to lock the lever against swinging movement; and operating means cooperable with said lever for effecting movement of the door.

75 20. In a sliding door opening and closing mechanism, the combination with a hasp-link; of a cooperable hasp-staple; an operating lever for said link, the lever overlying the link when the latter is engaged with the staple, said lever being movable in one direction to actuate the link to move the door, 80 and movable in another direction transverse thereto; and cooperable engageable means on the link and lever so arranged that when the latter is moved in said transverse direction the link may be pulled off of the staple there- 85 by.

In witness that I claim the foregoing I have hereunto subscribed my name this 25th day of April, 1928.
